UNITED STATES PATENT OFFICE.

JOHN B. H. LEONARD, OF MERIDEN, ASSIGNOR TO HIMSELF, LESLIE A. BELDING, OF MERIDEN, AND JAMES D. FRARY, OF NEW BRITAIN, CONNECTICUT.

IMPROVEMENT IN THE MANUFACTURE OF KNIVES AND FORKS.

Specification forming part of Letters Patent No. 58,269, dated September 25, 1866.

To all whom it may concern:

Be it known that I, JOHN B. H. LEONARD, of Meriden, county of New Haven, and State of Connecticut, have invented certain new and useful Improvements in the Mode or Process of Making or Attaching Handles to Knives, Forks, &c.; and to enable others skilled in the art to make and use the same, I will proceed to describe the mode or process by which this improvement is effected, referring to letters marked on the drawings, which indicate like parts in each of the figures.

The essential character of this improvement consists in the mode or process of making or securing soft-metal handles to or upon the shanks of hard-metal knives, forks, &c.

The object desired to be attained thereby is to produce a plain or ornamental handle by the process or mode of casting the metal upon the shank of the knife, fork, &c., by means of a mold or molds having a plain or ornamental inside surface, so as to produce a plain or highly-ornamental surface upon the sides or surface of the handles, simply by casting or pouring molten metal into molds having plain or highly-ornamental figures formed upon their inner surface, very much in the way or manner of forming tea-pot nozzles; or, in other words, by pouring molten metal into proper or desirably-formed molds, then after the metal has partially cooled to a certain depth or thickness around the sides the metal in the center of the handle (yet in a molten state) is poured out from the center of the handle through the same aperture *h* through which it was first poured into the mold or handle, after which the opening in the end of the handle is closed up by soldering, and thereby rendering it air and water tight.

In the accompanying drawings, Figure 1, *a* is a knife-blade, which is made much in the usual way. Its shank *c* is made square or in other shape, as may be desirable, having depressions *e* formed therein, for the purpose of

allowing the handle to compress itself more firmly thereto when the molten metal is poured thereon.

h is an aperture through which the remaining molten metal is poured out of the handle.

Fig. 2 is a fork, the tines *i* of which, with the lower end of the shank *i'*, are made in the common way. The shank *i'* is made about half the thickness of the shank *i*, and perforated or not, as desirable. After the shanks of these knives, forks, &c., are properly made or formed they (the shanks) are placed in the lower end of the mold, the inside of which is made the desired shape or figure required for a plain or highly-ornamental figure, into which the metal is poured while in a molten state, thus producing a knife or fork handle plain or embellished, according to the various patterns most desirable for the trade, without the necessity of being to the great expense and labor of fitting up dies, drops, presses, &c., thereby furnishing a plain, rich, and cheap article, which will produce a good finish without plating, and is at the same time susceptible of a fine plated finish.

In this way or by this means a great variety of styles and embossed figures can be produced at a very small expense, and at the same time produce an equally good, if not better, article for use and trade.

I believe I have thus shown the nature, construction, and advantage of this improvement, so as to enable others skilled to make the same therefrom.

What I claim, therefore, and desire to secure by Letters Patent, is—

The mode or process described of forming around and upon the tang of a knife or fork a hollow soft-metal handle, substantially as described.

JOHN B. H. LEONARD. [L. S.]
